UNITED STATES PATENT OFFICE

161,978

COMBINED PLANT HOLDER AND BRACKET THEREFOR

Jacob J. Weiman, Jamaica, N. Y.

Application March 25, 1950, Serial No. 8,760

Term of patent 3½ years

(Cl. D35—3)

REFERENCES CITED

The following references are of record in the file of this patent:

Gift and Art Buyer, August 1948, page 119, upper left center.

Decorative Home Furnishings, Syroco Wood, 1942, page 5, item #S1351.

Meier & Frank, 1949, catalog, page 24, item #1361.

Montgomery Ward & Co., Spring and Summer, 1949, page 726, item #32.

To all whom it may concern:

Be it known that I, Jacob J. Weiman, a citizen of the United States and a resident of Jamaica, in the county of Queens and State of New York, have invented a new, original, and ornamental Design for a Combined Plant Holder and Bracket Therefor, of which the following is a specification, reference being had to the accompanying drawing, forming a part thereof, in which:

Fig. 1 is a front view of a combined plant holder and bracket therefor, showing my new design.

Fig. 2 is a side view thereof.

Fig. 3 is a top view thereof.

I claim:

The ornamental design for a combined plant holder and bracket therefor, as shown.

JACOB J. WEIMAN.
